UNITED STATES PATENT OFFICE.

EDMUND S. SAYER, OF MANILA, PHILIPPINE ISLANDS.

CANTEEN.

1,032,086.

Specification of Letters Patent. Patented July 9, 1912.

Application filed August 29, 1911. Serial No. 646,701.

To all whom it may concern:

Be it known that I, EDMUND S. SAYER, a citizen of the United States, residing at Manila, Philippine Islands, have invented certain new and useful Improvements in Canteens, of which the following is a specification.

This invention relates to army canteens, and has for its object the provision of an efficient and thoroughly sanitary device of this character, the construction of which is such that access may be readily had to the interior thereof for the purpose of cleaning the canteen when the latter becomes foul, and also to permit regular inspection of the canteen along with the other military equipment.

A further object of the invention is to provide a canteen having a cup fitted to the bottom thereof and retained in position on the canteen by a jacket or cover, thus dispensing with the bulky separate cup now carried by soldiers and consequently reducing the equipment necessary for a march or campaign.

A further object is to provide a canteen including mating sections having interengaging parts and provided with a heat insulating jacket or cover, the bottom of which may be readily separated or spread laterally to permit the removal and replacement of the cup.

A further object is to provide a novel form of carrier, by means of which the canteen may be conveniently suspended from the belt so as not to interfere with or otherwise impede the movements of a soldier when marching.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

For a full understanding of the invention, reference is to be had to the following description and accompanying drawings, in which:

Figure 1 is a side elevation of a canteen embodying my invention, the cover or jacket being shown in section; Fig. 2 is a vertical

sectional view; Fig. 3 is an end view, showing the flaps of the cover separated to permit the removal of the drinking cup; Fig. 4 is a perspective view, showing the flaps of the cover separated and the drinking cup in position below the canteen; Fig. 5 is a side elevation, showing the construction of the carrier; Fig. 6 is a side elevation, showing the manner of supporting the cup; Fig. 7 is a detail vertical sectional view, illustrating a modified form of the invention.

Corresponding and like parts are referred to in the following description and indicated in all the views of the drawings by the same reference characters.

The improved canteen comprises a body portion, preferably elliptical in shape, as shown, and formed of mating sections 5 and 6 adapted to register with each other to form a liquid receiving chamber 7. The inner edge of the section 5 is provided with an annular reinforcement 8 having interior threads 9 which engage corresponding exterior threads 10 on a similar reinforcement 11 carried by the mating section 6, so that said sections may be readily separated to permit cleaning or scouring of the interior of the canteen when the latter becomes foul or when changing from one kind of liquid to another. The threads 9 terminate at approximately the center of the reinforcement 8 to form a shoulder 12, there being an annular pocket or recess 13 formed in said shoulder and adapted to receive a packing or gasket 14. One edge of the gasket 14 preferably projects a short distance beyond the shoulder 13 so that when the sections 5 and 6 are assembled, the material constituting the body of the gasket will be compressed so as to form a tight joint between the parts and thus effectually prevent leakage.

The metal or other material forming the section 5 is preferably stamped, pressed or otherwise formed with a laterally extending nipple 15, through which liquid may be introduced within or removed from the chamber 7, said nipple being threaded for engagement with a correspondingly threaded cap 16, to the inner face of which is secured a strip of rubber, cork or other material to render the cap air tight.

The exterior face of the section 6 is preferably flat, as indicated at 17, so as to lie flat against the body and provided with one

or more lugs 18 so that the section may be conveniently grasped and rotated to expose the interior of the liquid receiving chamber when cleaning the latter.

- 5 Attention is here called to the fact that the member 8 not only forms an annular reinforcement at the junction of the canteen sections 5 and 6, but also serves to prevent the edge of the canteen from becoming 10 battered or dented when subjected to rough usage, which would have a tendency to mutilate the threads and prevent the sections from being separated or assembled.
- 15 Detachably secured to the lower portion of the canteen, is a cup 19 designed to take the place of the separate bulky cup now forming a part of a soldier's equipment when on a march or campaign. The cup 19 is fitted over the lower portion of the 20 canteen and is provided on one side thereof with spaced pivotally mounted loops or handles 20 so that by swinging said loops laterally out of contact with the adjacent wall of the cup, and passing a stick, bar 25 or the like through said loops, the cup may be conveniently supported over a camp fire and used for heating coffee or other liquids. The handles or loops 20 are each preferably formed of a single length of spring wire 30 or metal, the ends of which are pivotally mounted in sockets 21 formed in an attaching plate 22. The lower end of each loop or handle is preferably reduced to form a laterally curved foot 23 adapted to 35 rest on the top of a stove, table or other support when the handles are swung outwardly, thereby to steady the cup and prevent the latter from tipping over. The upper and lower walls of the sockets 21 40 are formed with notches or depressions 24 adapted to receive the adjacent portion of the loops 20 when said loops are moved to extended position and thus lock said loops against accidental swinging movement. By 45 slightly separating the ends of the loops, said loops may be readily disengaged from the notches 24 so as to permit the loops to be swung laterally to inoperative position in contact with the cup. If desired, however, 50 the locking notches may be omitted and the loops attached directly to the body of the cup.

The canteen is provided with a cover or jacket 25 formed of canvas or other suitable material and also preferably constructed in two sections, the adjacent longitudinal edges of which are provided with eyelets 26 adapted to receive a lacing cord or tape 27. The inner face of the cover or 55 jacket 25 is preferably lined with a layer of felt, asbestos or similar heat insulating material so as to tend to maintain the liquid within the chamber 7 at the proper temperature. The eyelets 26 preferably terminate at approximately the center of the can-

teen to provide overlapping flaps or wings 27', which latter extend beneath the cup 19 and serve to retain said cup in position on the canteen. The flaps or wings 27' are held in closed position by suitable fastening devices, preferably in the form of snap buttons, the resilient heads 28 of which are secured to the inner edge of one of the flaps 27' for engagement with resilient sockets 29 secured to the inner face of the 71 mating flap. Thus it will be seen that by releasing the snap buttons and swinging the flaps 27' laterally, access may be readily had to the cup 19 for the purpose of removing or replacing the latter without the 81 necessity of entirely detaching the heat insulating jacket.

Secured to the jacket 25, on one side of the canteen and preferably at the flat surface 17 of the section 6, is a transverse strap 30, the stitching 31 of which terminates short of the center of the strap to produce a loop 32, to permit the passage of the upper or free end of a vertically disposed suspension strap 33. Secured to the 9 upper end of the strap 33, is a snap hook 34 by means of which the canteen may be conveniently suspended from the belt of a soldier so as not to interfere with or otherwise impede the movements of the soldier 9 when marching.

It will be understood that should the interior of the canteen become foul from the constant use of different kinds of liquids or from other causes, the interior of the chamber 7 may be readily cleansed and inspected by removing the jacket 21 and separating the sections 5 and 6, thus rendering the device thoroughly sanitary.

If desired, the metal forming the inner 1 ends of the canteen sections may be rolled to produce interengaging threads, as indicated at 35 in Fig. 7 of the drawings, in which event the metal forming one of the sections will be pressed laterally to form 1 a pocket 36 for the reception of a gasket 37 similar to the gasket 14, for the purpose of preventing leakage at the junction of said sections.

The canteens may be made in different 1 sizes and shapes and formed of metal or other suitable material without departing from the spirit of the invention.

Having thus described the invention, what is claimed as new is:

1. A canteen, including corresponding sections provided at their rims with annular reinforcing bands, said bands being formed with interengaging parts, and a nipple extending laterally from one of the 1 sections.

2. A canteen, including detachably united sections adapted to register with each other to form a liquid-receiving chamber, a cup fitted on the bottom of the canteen, a jacket 1

of pliable material forming a cover for the canteen and provided with flaps normally extending beneath the cup to prevent accidental displacement of the latter, and interengaging fastening devices carried by the flaps.

3. A canteen including detachably united sections adapted to register with each other to form a liquid receiving chamber and provided with interengaging parts, a cup nested on the bottom of the canteen, and a jacket forming a cover for the canteen and serving to retain the cup in position thereon.

4. A canteen including detachably united sections adapted to register with each other to form a liquid receiving chamber, one of said sections being provided with a nipple, a cup fitted on the bottom of the canteen, a jacket forming a cover for the canteen and provided with laterally movable flaps normally extending beneath the cup to prevent accidental displacement of the latter, and interengaging fastening devices carried by the flaps.

5. A canteen including mating sections adapted to register with each other to form a liquid receiving chamber, the inner ends of said sections being provided with annular reinforcements provided with interengaging threads, one section of the canteen being flat and provided with lugs, and the other section of the canteen being provided with a laterally extending nipple, a cup fitted to the bottom of the canteen and embracing both sections, and a jacket forming a cover for the body of said canteen and extending across and normally covering the cup.

6. A canteen, including corresponding sections provided at their rims with annular reinforcing bands, said bands having interengaging threads.

7. The combination with a canteen, of a cup fitted to the bottom of the canteen, co-acting loops pivotally mounted on the cup and movable laterally to extended position at substantially right angles to said cup, and means for locking the loops against pivotal movement when in extended position.

8. The combination with a canteen, of a cup fitted to the bottom of the canteen, co-acting loops pivotally mounted on the cup and having their lower ends reduced and curved laterally to form depending feet extending to a plane coincident with the bottom of the cup, said loops being movable laterally to extended position at substan-

tially right angles to the cup, and means for locking the loops in extended position.

9. The combination with a canteen, of a cup fitted to the bottom of the canteen, a plate secured to the cup and provided with spaced sockets, spring loops pivotally mounted in said sockets and movable to extended position at substantially right angles to the plate, and means for locking the loops in extended position, the lower ends of the loops being reduced to form depending feet extending to a plane coincident with the bottom of the cup.

10. The combination with a canteen, of a cup fitted to the bottom of the canteen, a plate secured to the cup and provided with spaced vertically disposed sockets, the upper and lower walls of which are provided with locking notches, and spring loops pivotally mounted in said sockets and adapted to enter the notches when the loops are swung outwardly in a lateral direction, thereby to prevent pivotal movement of said loops.

11. A canteen, including a body portion, a cup fitted to the bottom of said body portion, a sectional jacket forming a cover for the canteen, lacing cords connecting the upper portions of the jacket sections, the lower portions of said sections forming flaps normally extending underneath the cup to hold the latter in position on the canteen, and movable away from each other to expose the cup and permit it to be removed, and interengaging fastening devices carried by the flaps.

12. A canteen, including a body portion, a cup fitted to the bottom of the body portion, a sectional jacket forming a cover for the canteen and provided with separable flaps at the bottom of the body portion, and means for detachably holding said flaps together over the cup to hold the latter on the body portion.

13. A canteen, including a body portion, a cup fitted to the bottom of the body portion, a jacket covering said body portion and the cup and holding the latter in place, and a foldable handle carried by the cup and adapted to fold against the outer side thereof so as to allow the jacket to lie snugly against the adjacent side of the cup.

In testimony whereof, I affix my signature in presence of two witnesses.
